ERNEST A. HILDEBRANDT, OF INDIANAPOLIS, AND CHARLES McDONOUGH, OF BEECH GROVE, INDIANA

SUPERHEATER BRACKET

Application filed July 23, 1928. Serial No. 294,667.

This invention relates to means for supporting superheater pipes within the flues of boilers and has for its primary object the clamping together of the pipes whereby the 5 pipes are held out of contact and rigidly in respect one to the other and are held away from the flue surface so that there may be no grinding action as would otherwise occur should cinders work between the pipes and 10 the pipes be permitted to work or vibrate one over the other. Other objects reside in the supplying of such means in an extremely simple form lending itself to quantity production at a very low cost, and in the ease and 15 rapidity of installing such means.

The invention is described in the one particular form now best known to us as shown in the accompanying drawing, in which—

Fig. 1 is a fragmentary side elevation of 20 a short length of boiler flue showing the invention applied therein;

Fig. 2, a vertical transverse section on the line 2—2 in Fig. 1;

Fig. 3, a side elevation of the upper half 25 of the bracket; and

Fig. 4, a top plan view of the lower half of the bracket.

Like characters of reference indicate like 30 parts throughout the several views of the drawings.

The bracket is made in two parts, the upper part being generally designated by the numeral 10 and the lower part by the numeral 11. The lower part 11 of the bracket 35 is preferably made of steel about one-eighth of an inch in thickness and is formed to have a central upper portion 12 curved outwardly from the vertical axis from whence the material is curved back inwardly and downwardly from each side of the portion 12 to contact one side against the other, and each side then is curved outwardly downwardly and around to conform to the circumference 40 of the superheater pipes 13 and 14 to slightly beyond the vertical center lines of the pipes 13 and 14, from which points the material is dropped sharply downward at approximately 45 degree angles to form the legs 15 and 16. Slots 17 and 18 (Fig. 4) are cut

respectively at the lines on which the legs 15 and 16 are turned down.

The upper part 10 of the bracket is preferably formed of sheet steel approximately one-sixteenth of an inch thick and is pre-formed to fit snugly around the two pipes 13 and 14 as they are carried on the bracket part 11, Fig. 2, with the legs 19 and 20 extending vertically downwardly as indicated by the dash lines so that these legs 19 and 20 may 55 be extended through the slots 17 and 18 in the lower part 11, and the legs then bent over and upwardly against the under sides of the legs 15 and 16. The legs 15 and 16 rest against the flue 21. 60

The curved upper end 12 of the lower part 11 prevents the pipes 13 and 14 from jumping upwardly, since, to rise upwardly, the pipes 13 and 14 would have to move horizontally first to clear the portion 12, but the 70 bracket part 10 prevents such lateral travel.

The upper bracket part 10 is here shown with the legs 19 and 20 reduced slightly in width from the width of the bracket, Figs. 1 and 3, to form a shoulder to each side to act 75 as stops limiting the extension of the legs 19 and 20 through the slots 17 and 18, the slots being just long enough to permit the legs to slide therethrough freely.

While we have here described our invention in one particular form, it is obvious that structural changes may be made without departing from the spirit of the invention, and we therefore do not desire to be limited to the precise form as shown and described, nor 80 any more than may be required by the following claims.

We claim:

1. A pipe bracket for maintaining pipes in spaced alinement comprising a piece of 90 sheet metal formed to have a shoulder conforming to the curvature of the pipes, the metal being carried from the shoulder around and upwardly between one pipe and the next 95 adjacent pipe and thence bent around back against itself to return between the same two pipes forming a separator between the pipes and to continue around under the second pipe to form a shoulder thereunder, both shoulders of the bracket terminating close to ver- 100

tical planes through the centers of their respective pipes, said separator having a greater thickness above than at a plane through the center lines of the pipes, and legs extending from the shoulders having slots at their junctions with the shoulders.

2. A pipe bracket for maintaining pipes in spaced alinement comprising a piece of sheet metal formed to have a shoulder conforming to the curvature of the pipes, the metal being carried from the shoulder around and upwardly between one pipe and the next adjacent pipe and thence bent around back against itself to return between the same two pipes forming a separator between the pipes and to continue around under the second pipe to form a shoulder thereunder, both shoulders of the bracket terminating close to vertical planes through the centers of their respective pipes, said separator having a greater thickness above than at a plane through the center lines of the pipes, legs extending from the shoulders having slots at their junctions with the shoulders, and a sheet metal clamp shaped to pass around the pipes on the sides removed from the shoulders, said clamp having legs adapted to pass through the slots in the legs and to be bent against the under side of the legs.

3. A pipe bracket for maintaining pipes in spaced alinement comprising a piece of sheet metal formed to have a shoulder conforming to the curvature of the pipes, the metal being carried from the shoulder around and upwardly between one pipe and the next adjacent pipe and thence bent around back against itself to return between the same two pipes forming a separator between the pipes and to continue around under the second pipe to form a shoulder thereunder, both shoulders of the bracket terminating close to vertical planes through the centers of the respective pipes, said separator having a greater thickness above than at the plane through the centers of the pipes, legs extending from the shoulders, and means for retaining the pipes on the shoulders.

In testimony whereof we affix our signatures.

ERNEST A. HILDEBRANDT.
CHARLES McDONAUGH.
